UNITED STATES PATENT OFFICE.

ADOLF ZÖLLIN, OF BADENWEILER, AND EDUARD SCHREIBER, OF GUNDELFINGEN,
GERMANY.

MACHINE FOR PRINTING RAILWAY TICKETS AND THE LIKE.

Application filed August 29, 1922. Serial No. 585,039.

To all whom it may concern:

Be it known that we, ADOLF ZÖLLIN and EDUARD SCHREIBER, citizens of the German Republic, and residing at Badenweiler and 5 Gundelfingen, respectively, in Germany, have invented certain new and useful Improvements in a Machine for Printing Railway Tickets and the like, of which the following is a specification.

10 This invention relates to a machine for printing railway tickets, tickets for theaters, concerts or the like in the ticket office when they are to be issued. Railway tickets are to be printed by this machine with the name 15 of the end station of the journey, the class, the price and the date of issue. One of the objects of the invention is to reduce the number of manipulations for the different operations, so that the printing of the ticket 20 requires less time than is necessary at present to take the ticket from the pile. Only two manipulations are necessary, a pressure with the finger to adjust the die required for the printing and further the depression 25 of a lever to effect the printing and the severing of the ticket from the strip of paper. In order to accomplish this the dies for all the stations of the line are arranged upon the circumference of a drum, one such drum 30 being provided for each class, which has an automatically acting clockwork which is wound up again after each impression.

The drum is adjusted by the depression 35 of keys in such a manner that at the depression of a new key the previously operated key is automatically returned to the initial position, the die drum being thus liberated to adopt the new position with the aid of clockwork. If in this manner the desired 40 die has been brought into the range of the printing device the hand lever is depressed whereby the die is inked, the paper strip advanced and the ticket printed and severed from the strip.

45 A form of construction of the machine designed for the printing of railway tickets is shown by way of example on the accompanying drawings, wherein:

Fig. 1 is a front elevation of the machine 50 designed for printing tickets for four classes, the printing device for the third class being removed.

Fig. 2 shows the machine in side elevation, the end wall being removed.

Fig. 3 is a cross section on line A—B of 55 Fig. 2.

Fig. 4 illustrates the lever arrangement upon the rear wall of the casing designed for the winding up of the station drums for the four classes situated in front of 60 the device and for the winding up of the adjustment drum mounted upon the same shaft as the station drums.

Figs. 5 and 6 show respectively in side elevation and in front elevation the arrangement of the key board for the adjustment mechanism.

Fig. 7 shows a single key of the adjustment mechanism on an enlarged scale in longitudinal section.

Fig. 8 shows the development of the drum of the adjustment mechanisms having stop holes.

Fig. 9 is a vertical section through the middle of the printing- and severing device 75 on line C—D of Fig. 10.

Fig. 10 is a front elevation of the printing mechanism, the cover plate being removed.

Fig. 11 is a plan view showing the severing device arranged under the cover plate 80 and the printing pads.

Fig. 12 is a section through the severing device and printing pads on line E—E of 85 Fig. 11.

Fig. 13 shows in section the severing device in another position.

Fig. 14 is a section through the printing mechanism on line G—H of Fig. 15, the operating lever being shown in the position 90 in which it stands after the printing.

Fig. 15 is a rear elevation of the boxes designed to receive the printing mechanism.

Figs. 16 to 18 show constructional details of mechanisms for the control of the card-board- or control-strip. Fig. 16 is a section on line J—K of Fig. 17; Fig. 17 is a section on line L—M of Fig. 16 and Fig. 18 is a section on line O—P of Fig. 17.

Fig. 19 shows in section the ink reservoir 100 with roller connected with the clamping device for the paper strip.

Fig. 20 is a perspective view of the inking reservoir, and

Figs. 21 to 24 illustrate the locking device 105 for the printing mechanism. Fig. 21 is a side elevation, Fig. 22 a front elevation, Figs. 23 and 24 are two sections on enlarged

scale, the first illustrating the locking position and the second the released position.

The following are the principal parts of the machine:

5 I.—The drums carrying the station dies with the automatic winding up device, (Figs. 1 to 4).

II.—The adjustment mechanism for the station die drums (Figs. 5 to 8).

10 III.—The printing- and severing mechanisms (Figs. 9-20).

IV.—The locking device for the printing mechanism designed to prevent that, the 15 operation of the printing mechanism being started, it can be stopped without the printing of the railway ticket being completed (Figs. 21 to 24).

I.—*Station die drum with automatic winding up.*

The form of construction of the improved printing machine shown by way of example is designed for instance for four classes (Fig. 1). Consequently four drums 72a, b, 25 c, d are provided which carry the station dies (Fig. 4). These four drums 72a, b, c and d are mounted upon a common shaft 71 in a casing 70 in such a manner that their peripheries project into apertures 74 of the 30 front wall of the casing to be accessible at the printing of the ticket for the inking rollers as well as for the paper strip. At these apertures 74 of the wall 5 of the casing 70 the arrangements for receiving the printing mechanism and the box-shaped double casing 3 and 4 with hand lever 10 are 35 removably mounted.

In order to enable the adjustment of the 40 station die drums 72 for the desired station a cylinder 73 is keyed upon shaft 71 (as can be seen from Figs. 3 and 4) between the station drums 72a, b, c, d said cylinder being 45 designed for the adjustment mechanism which will be hereinafter described. As the adjustment of the station die drums requires each time a more or less great revolution of the station die drums, an automatically acting drive for the shaft 71 is required. This drive can either consist of a 50 clockwork or of a weight.

As, if a clockwork is used, this clockwork would have to be wound up from time to time, an improved weight rotated mechanism is used, according to this invention, 55 which at each printing of a railway ticket effects automatically the raising of the weighted lever required for the driving of the station die drums. The arrangement is such that, without regard to the amplitude 60 of the part-revolution which the station die drums execute at each printing of a ticket, always the full effect of the weighted lever is at disposal which serves for driving the shaft 71.

65 This is realized by the arrangement shown

in Figs. 2 to 4 which consists of a weighted lever 76 fulcrumed at 75 and having an adjustable weight 77. This weighted lever 76 holds in its fork-shaped bearing part a spring controlled pawl 78 which engages with a disk 79 having a wedge-shaped groove in such a manner that if the weighted lever 76 is lowered the grooved disk 79 is drawn along in the same direction. A spur wheel 80 is rigidly connected with the grooved disk 79 and meshes with a pinion 81 on shaft 71. The ratio of transmission of the spur wheel 80 and pinion 81 is selected so that at the greatest possible part revolution of the spur wheel 80 the pinion 81 can execute under all conditions somewhat more than a complete revolution. In this manner it is absolutely certain that at the adjustment of the drum for any station die whatsoever the drum can execute the revolution which is necessary for its proper adjustment, be it a part revolution or a complete revolution.

The control of the weighted lever 76 is effected by the arms 82 connected with the printing mechanism and designed to control the locking device for the printing mechanism which will be described hereafter. In order to ensure that the weighted lever 76 can be controlled from any of the printing mechanisms for the four classes a special lever transmission is provided, the construction and operation of which can be seen particularly in Fig. 4.

A lever 84 (Fig. 4) pivotable around a fixed axle 83 is hingedly connected by an articulated rod 85 and by an intermediary link 86 with the weighted lever 76 so that, if said lever arm 84 is raised the weighted lever 76 can be moved into the highest position (shown in dotted lines) with the aid of the arm 82 connected with the printing mechanism for the first class. In order to enable the weighted lever 76 to be controlled also by the arm 82 of the printing mechanism for the second class, a second two-armed lever 88 fulcrumed at 87 is provided which, by a link 91, is hingedly connected with the shorter of the two arms of lever 84. In this manner it is possible to control the weighted lever 76 each time the printing mechanisms for the first class and for the second class tickets are operated. A similar lever arrangement as described is arranged in inverse sense in the range of the arms 82 for the printing mechanisms for the third and fourth class tickets in order to ensure that at the operation of these printing mechanisms the weighted lever 76 be controlled also. For the arm 82 of the third class printing mechanism a lever 90 fulcrumed at 89 is connected by link 91a with a lever 93 fulcrumed at 92. The connection of the two lever systems 84 and 88 with 90 and 93 is effected by positive connection of the ends of the two levers 88 and 90 by means of 130

guide slot 95 and pin 94. In this manner the weighted lever 76 can be controlled always in the same sense from the arm 82 of each of the printing mechanisms for the four classes.

II.—Adjustment mechanism for the station dies.

The adjustment cylinder 73 keyed upon shaft 71 serves for adjusting the drums 72a, b, c and d which carry the station dies. This cylinder 73 has in its circumference adjusting holes 96 arranged as shown by the development Fig. 8. These adjusting holes are distributed over the surface of the adjusting cylinder 73 in such a manner that if a key 99 engages with one of the holes of the cylinder the station die designated by the key is adjusted.

In the form of construction shown each drum 72a, b, c and d is arranged for 100 station dies so that the adjustment cylinder 73 has 100 holes. Consequently the corresponding number of keys 99 must be provided (Fig. 1). Upon each key the name of the station is marked in a similar manner as the characters are marked on the keys of a typewriting machine.

The special construction of the keys is novel which permits in combination with an auxiliary device, that if a key is being depressed, the key which has been depressed previously is released automatically. The special construction of the key is shown in the sectional view Fig. 7, and Figs. 5 and 6 show the auxiliary devices which co-operate with the key. Each key consists of a bolt 98 acted upon by a spring and mounted in a sleeve 97. This bolt 98 carries at one end the key 99 and at the other end a cone 100. In the boring of bolt 98 the adjusting pin 101 is movably mounted and acted upon by a helical spring 102 in such a manner that it always projects from the cone 100.

The auxiliary device consists of a segment 103 pivotally mounted upon shaft 71. An abutment rail 103a serves for limiting the lowest position of said segment. The segment 103 has right angular holes 104 for the reception of the cone 100 of the keys. These holes 104 are arranged upon the segment 103 displaced with regard to one another in such a manner, that each key or the cone 100 of each key can come in engagement only with the hole 104 designed for this key. These holes 104 are large enough to leave sufficient play for the segment 103 if a key is depressed so that the key which has been previously depressed and which was retained in segment 103 by the edge of the cone being held by the hole, can now securely jump back through the action of its spring. If a new key is depressed the operation is as follows:

The previously depressed key is held in coupling position, as can be seen from Fig. 5, by the edge of the hole 104 gripping over the shoulder of the cone 100 owing to the fact that the segment 103 in consequence of 70 its natural weight has always the tendency to swing downward in the direction of the arrow.

If another key is depressed the segment 103 is raised by the cone of this key so far 75 that the cone 100 of the previously depressed key is released so that the key can be moved back through the action of its spring. The adjusting pin 101 of the key which has just been depressed will bear upon 80 the outer surface of the adjusting cylinder until this pin can engage with the corresponding hole 96 as soon as the weighted lever 76 causes the revolving motion of the adjustment cylinder 73 which happens if the 85 previously depressed key is being released. The correct adjustment of the drum for the station to be printed is thus effected and any accidental rotation of the station die drums is prevented. 90

III.—Printing and severing device.

The printing and severing devices are illustrated in Figs. 9 to 18. The printing mechanism consists, as can be specially seen 95 from Figs. 9, 10, 14 and 15, of two frames 3 and 4 which are pivotally mounted upon bolts 2, the frame 3 being removably mounted upon the end wall 5 of the casing 70 which is designed for the drums with the 100 station dies, the frame 4 having a lid 6 at its front end upon which on the one hand the counter plate 7 of the printing device designed for pressing the paper strip against the station dies and on the other hand the 105 severing device are arranged.

This severing device for the printed ticket consists of a spring controlled knife carriage mounted upon the lid 6 of the movable frame 4, said carriage being displaced in a direction opposite to the direction in which its spring acts by a stud 16 fixed on frame 3 with the aid of a lever 15 at the instant when frame 4 is made to register with frame 3 by the depression of 110 the hand lever 10. At this moment the printed ticket is cut off the paper strip 27 which is pressed against a counter-plate of the severing device.

In the lower part of the box-shaped frame 4 a hand lever 10 is pivotally mounted upon the two pivot pins 9, a nose 11 of said lever being acted upon by a spring 12 so that it is always held in the position shown in Fig. 9. The two arms of lever 10 have each 120 another nose 13 the upper curved part of each nose rolling, if the hand lever 10 is operated, upon the rollers 14 arranged upon the outer side of the frame 3. In this manner it is possible to make frame 4 pivot 125 130

4

around its axle so that if the hand lever 10 is moved in the direction of the arrow shown in Fig. 9, said frame 4 adopts the position shown in Fig. 14, in which it embraces entirely the inner frame 3. This movement serves for two purposes, first to press the paper strip by means of counter-plate 7 against the adjusted station die of the corresponding drum 72a to d and secondly to operate the severing device 8 shortly before the completed movement as the lever 15 which controls the knife is acted upon by the two pins 16 arranged upon the inner side of frame 3 in such a manner that the knife carriage is raised. By the movement of the frame 4 through the intermediary of the hand lever 10 the following operations are further to be effected.

1. The inking of the station die, and
2. The advance of the paper strip 27 upon which the printing has to be effected for the length of the railway ticket and further the feeding of the control strip 27a. This is effected with the aid of two toggle joints 25 which are arranged at either side between the two frames 3 and 4.

These toggle joints are composed each of a lever arm 18 fulcrumed at 17 in frame 3 and of a lever 20 fulcrumed at 19 upon the inner side of frame 4 (Figs. 9 and 10).

These two levers 18 and 20 are hingedly connected the one with the other at 21. The levers 18 are connected by articulated rods 22 with the carriage 23 guided upon guide rails 24 adapted to slide between the two rails 55 in frame 3. This carriage 23 consists, as can be specially seen from Figs. 16, 17 and 18, of two parts separated by a gap 28 through which the paper strips 27 and 27a are fed which come from the slits 26 and 25. The two parts of carriage 23 are generally pressed the one upon the other by the action of a spring 29 so that the paper strips 27 and 27a are held between said parts. As the paper strips 27 and 27a are to be held only at the descending movement of the carriage 23 if they have to be advanced for the printing of the railway ticket, an arrangement is provided which is designed to 50 release the paper strip 27 and the control strip 27a before the carriage 23 begins to ascend. With this object in view the bolt 30 which is acted upon by spring 29 is pushed back by a cam 31 shortly before the carriage has arrived at its lowest position 55 so that the gap 28 is enlarged. A clamping device 32-33 (Fig. 17) serves to maintain the parts of the carriage at the position of enlarged gap during the ascending movement so that the two paper strips are not pulled up with the carriage, said clamping devices retaining the bolt 30 and consequently the clamping rail 32a of the carriage 33 until the carriage has arrived at its 60 highest position. At this moment the

clamping device is released as the projecting stud 33 (Figs. 18 and 14) strikes against the axle 2 which serves at the same time as abutment (Fig. 9). The paper strip 27 and the control strip 27a can now again be 70 clamped between the two parts of carriage 23 under the influence of spring 29. A second holding device is provided to securely hold the strips 27 and 27a in the position to which they have been brought by the 75 descent of the carriage, this second holding device gripping the paper strips directly after the descent of the carriage and holding the same during the printing and severing. This holding device consists, as shown 80 in Figs. 9, 10, 14, 19, of a transverse piece 35 which is movably suspended to shaft 37 by means of two arms 36. These arms 36 are under the influence of pressure springs 38 designed to hold the paper strip guided 85 below the blade springs 34 over a support 39 until this holding device 34 to 38 is released. As the paper strips 27 and 27a must be held at this point only during the 90 ascending movement of the carriage 23 but remain free if the carriage descends, a releasing device for this clamping device is provided. This releasing device consists of a blade spring 40 (Figs. 10 and 14) which reaches under a projecting nose 41 of the 95 transverse piece 35 and holds this piece with the blade spring 24. In order to ensure that, also in this case, the release is effected in proper time shortly before the upward movement of the carriage has come to an end 100 the following releasing device is provided:

Upon the second articulated rod 22a a stud 43 (shown in Fig. 10 in dash lines) is mounted which is designed to grip under the right hand side nose 44 of the transverse piece 35 105 shortly before the highest position is reached. Simultaneously with the lifting off of the transverse piece 35 and the release of the paper strip resulting therefrom the blade spring 40 becomes free to grip under 110 the nose 41 of the transverse piece 35 whereby the clamping device 34 rests open until the same is released again by the button 41 at the downward movement of the carriage.

The printing of the railway ticket is effected in two operations.

At the printing of one railway ticket the preliminary impression for the next following ticket is already made. At this preliminary printing the text which remains 120 always the same, as station of depart, class and the consecutive number and the date are printed. This is the first operation. At the second operation the name of the station of destination and the price are printed on the 125 ticket. At the same time the control strip is printed in two operations. It is not necessary that the station of depart be printed upon the control strip as there cannot be any 130 doubt as regards the origin of the strip. In

accordance with the railway tickets the control strip is printed at the first operation with the consecutive number and at the second operation with the name of the station 5 of destination and the price. As the printing is divided into two printing steps, two printing mechanisms are required. The printing mechanism for the second operation consists of the dies of the drums 72a,

10 b, c, d for which the printing pad 56 (Figs. 11, 12, 13) designed to press the paper strips 27 and 27a is arranged upon the inner surface of the lid 6. A separate printing die 47 comprising two numbering devices 46 for 15 the two paper strips 27 and 27a is provided which is coupled with the guide ribs 24 of carriage 23 in such a manner that this printing die 47 is obliged to participate in the up and down movement of the carriage. 20 This printing die 47 is oscillably mounted upon the axle 48 positively guided between the two parallel rails 55 so that it can execute under the influence of the guide curves 49 at the up and down movement at the 25 same time a movement in horizontal direction. This is necessary for the inking and in order to bring the die into the printing position required for the printing of the strips 27 and 27a. For inking this die 47

30 which comprises the numbering devices 46 the station of depart, the date and class, the inking receptacle 50 with inking roller 51 is provided. The receptacle 50 designed to receive the printing pad is oscillably mounted 35 by means of trunnions 52 (Figs. 19 and 20) upon the support 39 for the pressing device 35 and it is controlled by a small spiral spring 54 (Fig. 19). This movable arrangement of the printing pad is necessary to 40 make free at the top position the way for the printing die 47 which is moved toward the right under the influence of the guide curve 49 as soon as it has reached its lowest position. With this object in view the ink 45 receptacle 50 has a lateral stud 57 (Fig. 20) which at the downward movement is in contact with the sliding rail 55 and pushes back the inking roller 51 so that the path for the printing die 47 is made free for the ascent.

50 For inking the die mounted in the drum a second inking device 58 is provided which has an inking roller 59 connected by means of elastic connecting rods 60 with the guide ribs 24 designed to communicate a reciprocating movement to the other parts of the device. In order to ensure that the inking roller 59 comes in contact with the adjusted die only for a short moment during the downward movement of the same, curved 55 guides 61 are arranged for this inking roller in the inner frame 3, these guides being arranged so that shortly before the completion of the downward movement the inking roller 59 is pressed against the adjusted station 60 die and effects the inking in rolling over

said die. At the next moment the inking having been done the inking roller is lifted off whilst the station die continues to descend so that the path for the printing pad 56 is made free. 62 and 63 are merely protecting plates which, elastically arranged, leave between them a gap which is only so large that the paper strips can be brought in contact with the drums.

65 The operation of the numbering mechanisms 46 is effected with the aid of the spring controlled feeding bolts 64 mounted upon the abutment 7, two of such feeding bolts 64 being provided as can be seen from Fig. 11, one for the numbering device for 80 the railway ticket and the other for the numbering device for the control strip.

75 It may further be remarked that in the form of construction shown by way of example the freely accessible paper rolls and strips ought to be locked up in the practical use in order to prevent the fraudulent manipulation, specially of the control strip.

IV.—Locking device for the printing apparatus.

90 In order to prevent that a movement of the hand lever 10 of the printing device once started can be stopped without completion of the printing of a ticket a special locking device is provided. This locking device is shown in Figs. 21 to 24, Figs. 21 and 22 showing the same in elevation seen from two different sides, Figs. 23 and 24 being a longitudinal section which show the locking device at about 95 double the size, Fig. 23 showing the same in the locking position and Fig. 24 in the released position. This locking device consists essentially of a rod 105 suspended to the top plate of box 70 and designed to serve 100 as guide for a casing 106. This casing can be moved up and down by the two levers 82, 82 rigidly connected with the frame 4 of the printing device which has to be moved. The upward movement can take 105 place at any time, but the downward movement only, if the forward movement and consequently the printing of the ticket have been completed. With this object in view a locking pawl 108 controlled by a spring 107 110 is pivotally mounted in a recess of rod 105. This locking pawl 108 places itself against the inner wall of casing 106 in such a manner that the axial displacement of said casing upon the rod 105 in downward direction is impossible.

115 In order to permit the downward movement of the casing after the printing has been completed a separate locking for the pawl 108 is provided which consists of a 120 ring 110 controlled by a spring 109 and designed to grip behind a nose 111 of the locking pawl 108 when, after the casing 106 has arrived at its highest position, the locking pawl 108 is slightly raised by striking 130

against the cross pin 112 (confer position Fig. 24). The locking pawl 108 is thus released. The reinsertion of the locking pawl 108 is effected by the adjusting screw 113 5 screwed into the casing 106 and serving as abutment for the ring 110. By this short contact the locking ring 110 is pressed downward against the action of spring 109 before the casing 106 arrives at its lowest 10 position, the locking pawl 108 being thus released.

We claim:—

1. Machine for printing, before the issue of the same, railway tickets and the like 15 with continuously varying text comprising in combination a main shaft, several printing drums upon said shaft, station dies mounted upon said drums, an automatically acting winding-up device for said printing 20 drums, an adjustment mechanism for adjusting said printing drums according to the desired text, a key board the keys of which adjust the position of the adjustment device, a printing and severing mechanism for each 25 drum, a cardboard strip for each drum for the tickets to be printed, a control strip for each drum for controlling the tickets printed and issued, and a hand lever for operating 30 said printing and severing mechanisms in two steps so that at the first step the two strips are advanced and at the second step the two strips are printed and the printed ticket is severed from the strip.

2. Machine for printing railway tickets 35 and the like comprising in combination a frame, a main shaft revolubly mounted in the frame, several printing drums one for each class mounted upon said shaft, station dies mounted on said drums, an adjustment 40 cylinder mounted upon said shaft between said printing drums having as many perforations as there are station dies, a pivotally mounted weighted lever designed to revolve said shaft, a key board comprising as many 45 keys as there are perforations in the adjustment cylinder, the key which is being depressed engaging with the perforation of the cylinder which corresponds to the station die to be printed, a cardboard strip for 50 each drum for the tickets to be printed, a paper strip for each drum for the control of the impressions made, means for intermittently feeding these strips, a severing apparatus for each drum for cutting off the 55 printed ticket, a hand lever for operating said printing and severing mechanisms, a rod and lever system connecting said weighted lever with said hand lever so that the same is raised after each printing operation.

3. Machine for printing railway tickets and the like comprising in combination a frame, a main shaft revolubly mounted in the frame, several printing drums one for 60 each class mounted upon said shaft, station

dies mounted on said drums, an adjustment cylinder mounted upon said shaft between said printing drums having as many perforations as there are station dies, a pivotally mounted weighted lever, a ratchet mounted 70 upon the pivot pin of said weighted lever, a pawl hingedly mounted upon said lever engaging with said ratchet, a toothed wheel of much smaller diameter than said ratchet keyed upon said main shaft and meshing 75 with said ratchet, a key board comprising as many keys as there are perforations in the adjustment cylinder, the key which is being depressed engaging with the perforation of the cylinder which corresponds to the station die to be printed, a cardboard strip for 80 each drum for the tickets to be printed, a paper strip for each drum for the control of the impressions made, means for intermittently feeding these strips, a severing apparatus for each drum for cutting off the printed ticket, a hand lever for operating said printing and severing mechanisms, a rod and lever system connecting said weighted lever with said hand lever so that 90 the same is raised after each printing operation.

4. In a machine for printing tickets as described the rod and lever system for connecting the hand lever with the weighted 95 lever comprising a lever projecting from each printing and severing mechanism, four two-armed levers pivotally mounted and designed to be acted upon each by the lever of the corresponding printing and severing 100 mechanism, links for hingedly connecting said two-armed levers with one another, and a rod and link connecting said weighted lever with said set of two-armed levers.

5. In a machine for printing tickets as 105 described the means for locking and releasing the adjustment cylinder consisting of a segment loosely mounted upon the main shaft so that its curved wall covers the perforated adjustment cylinder, having holes which are larger than those of the adjustment cylinder but correspond with the same in position, the keys of the key board having each a central boring, a cone at the 110 end of each key designed to engage with the corresponding hole of the segment to hold the segment and to release the same if at the depression of another key the segment is slightly moved and a spring controlled 115 rod in said body of each key designed to engage with the corresponding perforation of the adjustment cylinder to lock the same in the adjusted position.

6. In a machine for printing tickets of 125 the type described the keys consisting each of a spring controlled bolt having a central boring at its lower end, the key board marked with the name of the station to which the type corresponds, a perforated cone at the lower end of the key, a spring 130

controlled coupling pin in said boring of the bolt designed to engage with the corresponding hole of the adjustment cylinder for stopping the same, said cone being designed to retain the key in the operative position by its engagement with an oblong hole of the segment upon the adjustment cylinder.

7. In the machine for printing tickets of the type described the printing and severing mechanism consisting of an inner fixed frame and of an outer movable frame pivotally connected with said fixed frame, a spring controlled hand lever pivotally mounted upon said movable frame, a curved extension at the upper end of said hand lever, an abutment roller upon said fixed frame, the printing pads fixed upon the inner surface of the lid of said movable frame and the severing mechanism, said printing pad serving to advance the cardboard strip for the tickets to be printed and the control strip and said severing mechanism serving to cut off the ticket which has been printed if the movable frame is pressed upon the fixed frame with the aid of said hand lever.

8. In the machine for printing tickets of the type described the mechanism for inking the printing die if the movable frame is pressed upon a fixed frame comprising in combination with the fixed frame and with the movable frame two toggle levers between said frames composed each of a lever pivotally mounted upon the fixed frame and of a lever pivotally mounted upon the movable frame, means for pivotally connecting said two levers the one with the other, a carriage movably mounted at the upper end of the

fixed frame composed of two parts between which the passage for the ticket strip and for the control strip is formed, rods connecting said toggle levers with said carriage.

9. In the machine for printing tickets of the type described the severing device for the ticket strip comprising in combination with the fixed frame and with the movable frame, a knife carriage arranged upon the lid of said movable frame, a stud upon the movable frame designed to act upon said knife carriage, a lever designed to push said stud forward if the movable frame is being pressed upon the fixed frame.

10. A locking device for the printing apparatus comprising in combination with the fixed frame the movable frame and the hand lever for operating said movable frame a suspended rod, a casing positively connected with said movable frame guided upon said rod, a spring controlled pawl upon said rod bearing against the inner surface of said casing and designed to prevent the axial displacement of said casing, an abutment for releasing said locking pawl, a spring controlled locking ring for said pawl, and a second abutment designed to act upon said locking ring for releasing the pawl shortly before the completion of the downward movement of said casing.

In testimony whereof we have hereunto set our hands in the presence of two subscribing witnesses.
